United States Patent Office

Des. 183,062
Patented June 17, 1958

183,062

EMBOSSSED PLASTIC SHEET MATERIAL

Walter J. Platte, St. Louis, Mo., assignor to The B. F. Goodrich Company, New York, N. Y., a corporation of New York

Application May 24, 1957, Serial No. 46,339

Term of patent 14 years

(Cl. D87—3)

The figure is a plan view of an embossed plastic sheet material showing my new design, a unit being enclosed within the dot and dash lines.

I claim:

The ornamental design for an embossed plastic sheet material, as shown and described.
